APPARATUS FOR CONTROLLING THE CONCENTRATION OF SOLUTIONS WHICH TEND TO FOAM

Paul A. Keene, Syracuse, N. Y., assignor to Allied Chemical & Dye Corporation, a corporation of New York

Application March 11, 1946, Serial No. 653,675

5 Claims. (Cl. 137—68)

1

This invention relates to control apparatus for controlling the concentration of solutions which tend to form foam or suds; for example, alkaline solutions containing organic detergents. In the specifications hereinafter, and claims, the term "foam" is used in a broad sense and is intended to include suds.

In dish washing machines, for example, it is common practice to spray a detergent solution from a body thereof on the dishes, after which the dishes are rinsed by spraying them with hot rinse water. The rinse water usually collects in the body of wash solution where it causes some dilution, with consequent change in the concentration of this solution. A portion of the wash solution from the body thereof flows through an overflow pipe during operation, thus maintaining the level of the body of solution substantially constant. As successive racks of dishes are washed, the washing and rinsing cycles are repeated. During the course of the washing, detergent should be added to the wash solution to maintain, as nearly as practicable, a uniform concentration of detergent therein, i. e. to replace the detergent which is wasted in the overflow, and also that which reacts in each cycle to effect removal of dirt and other constituents washed from the dishes. For best results, the concentration of detergent in the wash solution should be maintained within fairly narrow limits. Concentrations below the predetermined limit produce inefficient washing and concentrations above this limit result in unnecessarily large losses of detergent.

It has been proposed to control the concentration of such washing solutions within relatively narrow limits by means of a controller involving an electrode disposed in the solution and responsive to changes in concentration, which electrode controls the feed of detergent solution to the wash solution.

When such controllers are employed in washing machines employing detergent solutions, such as are commonly used, which solutions in use tend to foam, certain difficulties are encountered. For example, when the foam contacts the control electrode, due to the fact that the foam has a very much higher resistance than the solution from which it arose, the electrode registers the resistance of the foam, and causes the controller to remain in the operating position, so that detergent continues to be fed even though the concentration of the solution is above the desired predetermined value. This continuance of feed of detergent solution results in the production

2

of more foam and may eventually lead to the solution overflowing the washer.

Among the objects of this invention is to provide a controller for maintaining the concentration of a solution, e. g. a detergent solution, within narrow limits, which controller overcomes the above-mentioned difficulty, i. e. interrupts or prevents the supply of detergent to the solution when foam is produced, and rises to a point above the normal solution level, and as soon as the foam dies down, permits the control electrode to function to maintain the concentration within narrow limits. Other objects and advantages of this invention will be apparent from the following detailed description thereof.

In the preferred embodiment illustrated on the drawing, the invention is shown incorporated in a dish washing machine and the present description will be confined to the present illustrated embodiment of the invention. It will be understood, however, that the novel features and improvements are susceptible to other applications such, for example, as can washing machines or other machines in which it is desired to maintain within narrow limits the concentration of a solution which tends to foam in use. Hence, the scope of this invention is not confined to the embodiment herein described. The invention is broadly applicable to the control of concentrations of any solute in a solution the conductivity of which varies with the concentration of the solute; for example, aqueous solutions of electrolytes.

In the accompanying drawings,

35 Fig. 1 is a diagrammatic vertical sectional view partially in elevation illustrating a dish washing machine embodying this invention;

Fig. 2 is a wiring diagram showing a bridge type of electrical control embodying this invention; and

40 Fig. 3 a fragmentary vertical section on an enlarged scale, as compared with Fig. 1, showing one form of detergent dispenser which may be associated with the washing machine.

45 Referring to Fig. 1, the dish washing machine comprises a housing 10 in which racks of dishes 11 are placed on perforated supports 12. Top and bottom wash sprays 13, 14 are arranged to be supplied with wash solution under pressure through branch pipes 15, 16 from a motor driven pump 17, the suction intake 18 of which is in communication with a body of detergent solution 19 disposed in a tank 20 positioned near the bottom of the washing machine. Hot rinse water 55 is supplied from a pipe 21 having branches 22,

23 extending to the top and bottom rinse sprays 24, 25. It will be understood that the washer shown in the drawing represents one well-known type of washer and the present invention may be applied not only to this washer but to other types also.

Desirably the detergent solution may be a caustic soda, soda ash, modified soda or other alkaline solution, containing an organic detergent such, for example, as that sold under the trade-mark "Nacconol," (salts of alkyl benzene sulfonates, the alkyl group of which has an average carbon content of from 12 to 18 carbon atoms), or that sold under the trade-mark "Nytro-n," (organic nitrosation-sulfitation products disclosed in United States Patent No. 2,265,993 granted December 16, 1941) or other solutions, the conductivities of which vary with the concentrations of the solute, solutions with higher concentrations having higher conductivities.

In the operation of the dish washing machine, the dishes 11 are washed by operating pump 17 for a predetermined period of time, and then this pump is stopped and the dishes are rinsed by supplying relatively hot rinse water from the sprays 24, 25. Each rack of rinsed dishes, after rinsing, is removed and replaced by another rack of dishes to be washed, and the cycle of operation repeated. Rinse water from each cycle of operation dilutes the body of solution 19 and causes some of the latter to flow through the overflow pipe 26, the top of which is disposed at such elevation within tank 20 as to maintain the solution therein at the desired level. Thus the concentration of detergent in the body of solution 19 is progressively reduced by the reaction of the detergent with food and other material on the dishes, by the dilution of the solution with the rinse water, and due to the overflow through pipe 26.

Detergent solution is supplied to the washing machine from a dispenser 27 mounted on a bracket support 28 fastened to the side of the washer. The dispenser 27 is desirably in the form of a cylindrical container 29 having a base 30, a discharge outlet 33 leading from the dispenser into a discharge conduit 34, which in turn leads into the washer, a downwardly sloping plate 31 disposed just above the base 30 and extending completely across the container 29, and a concavo convex vertically extending member 32 having its ends welded or otherwise fastened to the inner walls of the container 29, and extending from near the top of container 29 to the plate 31. Thus, there is produced a channel 35, semi-circular in cross-section, extending vertically along the inner wall of container 29, and occupying a minor portion of the volume thereof, and a compartment 36 occupying a major portion of the volume of container 29, which compartment receives solid detergent to be dispensed. The concavo convex portion of member 32 defining a sidewall of compartment 36, as shown in Fig. 3, is perforated to place the compartment 36 in communication with channel 35; for example, the intermediate portion of member 32 may be a screen desirably of 30-mesh. A perforated distributor plate 37 is disposed across the top of compartment 36. A cover 38 may be provided for the container 29 to prevent steam and vapor escaping when the cover is in closed position.

A solenoid housing 39 is disposed above water reservoir 40 which extends through cover 38. Water reservoir 40 has in the base thereof an overflow pipe 41 through which the reservoir communicates with channel 35. The base of

5 reservoir 40 is also provided with a valve opening or seat 42, flow through which is controlled by valve plug 43. Opening 42 communicates with a spout 44, the discharge outlet of which is disposed above distributor plate 37. Water, preferably hot water at a temperature of 100° F., is supplied to reservoir 40 through water inlet line 45 which may be a branch line from the main rinse line 21. Valve plug 43 is fastened to one end of valve stem 46, the other end of which is secured by a valve hinge pin 47 to the armature 48. Stem 46 passes through a flexible sleeve 48' which is fastened to the base wall of housing 39 and is secured to stem 46, thereby preventing moisture from entering the solenoid housing 39.

15 On activation, the solenoid armature 48' is raised, pulling the valve plug 43 from its seat against the action of a spring 49. Water already present in reservoir 40, along with fresh water from line 45, passes through opening 42 to the spout 44, and thence to distributor plate 37 where it passes over or through the detergent in the compartment 36. The resulting concentrated detergent solution flows through channel 35, discharge outlet 33 and conduit 34 into the washer, where it mixes with the body of wash solution 19. As the quantity of water required to dispense the required amount of detergent is small, of the order of 8 to 10 gallons per hour, the dilution of 20 the wash solution 19 by the minor portion of this water flowing through overflow pipe 41 and channel 35 and not passing through the solid detergent is negligible.

25 The controller, as shown in Fig. 2, involves a control circuit 50 and a main circuit 51. The latter is energized from an alternating current source which is connected to the input terminals of the primary 52 of a multi-coil transformer 53. Disposed in the main circuit 51 is the operating 30 solenoid 48, a switch 54 which is normally open but which is adapted to be closed, as hereinafter described, by the control circuit to cause current to flow through the main circuit to energize solenoid 48, and a signal lamp 55 shunted across the 35 solenoid 48 and showing when current is flowing in the main circuit, and the dispenser is, therefore, operative to dispense detergent solution to the washer.

35 The control circuit comprises variable resistors 56, 57 in a Wheatstone bridge arrangement, to one arm 58 of which are connected conductors 59, 60, leading to a control electrode 61. This electrode may be of any well-known type for measuring conductivities of solutions, and desirably consists of a pair of closely spaced platinized rods in a common casing. It is disposed in the washer within the body of solution 19 as shown in Fig. 1. In parallel with the control electrode 61 is an auxiliary electrode 62. This electrode 40 desirably may consist of two metallic plates 63, 64, say each approximately 2" long and 2½" wide and closely spaced, say one-half inch apart, so that the electrode has a lower resistance when foam fills the space between the plates than the 45 resistance of electrode 61 when submerged in a solution of the desired concentration. The presence of foam between plates 63, 64 in effect short circuits the control electrode 61, i. e. materially decreases the resistance in the arm 58 of the 50 Wheatstone bridge. As shown in Fig. 1, electrode 62 is located at a point above the normal level of body of solution 19 where the foam will reach it quickly. Consequently, in operation the dispensing of detergent solution will be stopped 55 when foam reaches the electrode 62, which will

take place before enough detergent is added to cause the solution to overflow the machine. As soon as the foam dies down due, for example, to the presence of soil in the wash water, the electrode 62 is left free and clear, becoming an infinite resistance, and consequently exerting no further effect on the control electrode 61.

Secondary coils 65, 68 of transformer 53 are connected by conductors with points 66, 67 of the Wheatstone bridge. Secondary coil 68 supplies current to the filaments 69, 70 of electronic tubes 71, 72. Tube 71 desirably is a conventional triode or pliotron, and tube 72 desirably is of a type to produce a higher emission of electrons, such as the well-known thyratron. Tube 71, as conventional, comprises a cathode 72', a grid 73 and an anode 74. The tube 72 comprises a cathode 75, a grid 76, a screen electrode 77 and an anode 78.

Secondary coil 79 of the transformer 53 is in circuit with points 80, 81 of the Wheatstone bridge. Located in this circuit is the grid circuit of the tube 71 as shown in Fig. 2. The output anode circuit of the tube 71 includes a resistor 74' across which the input circuit of the tube 72 is shunted. In the output anode circuit of tube 72 is disposed relay 82 for operating switch 54 in the main circuit 51. Resistor 74' is such that when the current flowing through the output anode circuit of tube 71 reaches a certain value, the potential drop across the resistor 74' causes the tube 72 to pass sufficient current through its anode circuit to operate the relay 82, to close switch 54.

The control circuit hereinabove described, except for the electrodes 61, 62 and the lead wires connected thereto, and the parts of the main circuit except for the solenoid 48 and signal lamp 45, are all preferably disposed in a control box 83 which may be positioned on support 28 next to dispenser 27. The control is, therefore, readily applicable to existing washers not equipped with controls, particularly in cases where it is desired to supply such washers with dispensers of the type herein described. When modifying a washer to embody this invention, it is only necessary to install the dispenser and control box on the side of the washer, connect the discharge of the dispenser with the washer, and place the electrodes 61, 64 within the washer in the relative positions shown.

In operation, resistance 57 is set at a point previously determined by calibration, which point is dependent upon the desired concentration of the detergent used. Resistance 56 is likewise set at a point previously determined by calibration, which point is dependent upon the temperature of the body of wash solution 19. Since the grid 73 and plate 74 of tube 71 are approximately 180° out of phase, an increase in the resistance of the solution, due to a decrease in concentration, causes a gradual increase in the instantaneous voltages between the grid 73 and cathode 72' which in turn causes a decrease in the current flow through the resistor 74'. The control voltage developed across resistor 74', applied across the control grid 76 and cathode 75 of tube 72, is sufficient to prevent tube 72 from firing before the concentration of the solution starts to decrease. When the decrease in voltage drop across resistor 74', resulting from the increase in resistance across the electrode 61, reaches a critical value, depending upon the tube employed, the control grid 76 loses control and the tube 72 fires which causes current to flow through the 75 of solution.

relay 82 which effects closing of the switch 54 causing current to flow through the solenoid 48. The armature 48' of the solenoid 48 is thus raised against the action of spring 49, to move valve plug 43 from its seat 42. Water in reservoir 40 along with that supplied thereto through line 45 flows through opening 42 and spout 44, to the distributor plate 37, and flows in contact with the detergent, the resultant solution passing through passageway 35 into and through passageway 34, into the washer where it collects in tank 20.

As the concentration of the solution in tank 20 increases, the resistance across the electrode 61 decreases, and a gradual decrease in the instantaneous voltages between the grid 73 and cathode 72' of tube 71 occurs, which causes an increase in the current flowing through resistor 74'. The resultant increase in voltage appearing across the control grid 76 and cathode 75 of tube 72 finally reaches a point where the control grid 76 resumes control and extinguishes the tube, stopping the current flow through the relay 82, deenergizing it, and opening the switch 54, whereupon, under the influence of spring 49, valve stem 46 returns valve plug 43 to its seat 42. Water thereafter supplied through line 45 flows from reservoir 40 through overflow pipe 41 into and through passage 35 and not to the body of detergent maintained in compartment 36 of the dispenser 27.

When foam is produced, as is frequently the case when employing a solution containing an organic detergent, and the foam rises to a point such that it enters between the plates 63, 64 of the auxiliary electrode 62, the resistance in the arm 58 of the Wheatstone bridge is thereby reduced so that, as hereinabove described, valve plug 43 is seated in seat 42 and the water flows through channel 35 and not through the body of detergent. Hence, as long as foam is present at a level such that it contacts the auxiliary electrode 62, no detergent is fed to the washer. When the foam dies down, the auxiliary electrode 62 is left free and clear, exerting no further effect on the control electrode 61 and permitting this electrode to maintain the concentration of the detergent in the washer within the desired narrow limits.

Since certain changes may be made in the above construction and different embodiments of the invention could be made without departing from the scope thereof, it is intended that all matter contained in the above description or shown in the accompanying drawing shall be interpreted as illustrative and not in a limiting sense.

What is claimed is:

1. A control for maintaining within narrow limits the concentration of a body of solution which tends to foam, which comprises in combination, a control electrode responsive to changes in concentration in said body of solution, a control circuit in which said electrode is disposed, said control circuit effecting feed of material to said body of solution responsive to changes in concentration to maintain said concentration within said narrow limits and an auxiliary electrode in said control circuit and disposed above the normal level of said body of solution, said auxiliary electrode being adapted to be contacted by foam rising above the normal level of said body of solution, and while thus contacted rendering the control circuit inoperative and preventing the feed of further material to said body of solution.

2. A control for maintaining within narrow limits the concentration of a body of solution which tends to foam, which comprises in combination, a control electrode responsive to changes in concentration in said body of solution, a control circuit in which said electrode is disposed, said control circuit effecting feed of material to said solution responsive to changes in concentration to maintain said concentration within said narrow limits, and an auxiliary electrode 10 disposed above the normal level of said body of solution and arranged to be contacted by foam produced in said body of solution, said auxiliary electrode being connected in parallel with the control electrode and when contacted by said foam rendering the control electrode inoperative.

3. A control for maintaining within narrow limits the concentration of a body of alkaline solution which tends to foam, which comprises in combination, a dispenser for feeding alkaline solution to said body of solution, a control electrode disposed in said body of solution, means operated by said electrode for causing said dispenser to feed alkaline solution to said body of solution when the concentration thereof falls below a predetermined value, means for interrupting the feed of said alkaline solution to said body of solution when the concentration thereof is restored to said predetermined value, an auxiliary electrode disposed above the normal level of said body of solution and arranged to be contacted by foam produced in said body of solution, said auxiliary electrode being connected in parallel with the control electrode, and when contacted by said foam functioning to short circuit said control electrode to render it inoperative and prevent feed of further solution to said body of solution.

4. A control for maintaining within narrow limits the concentration of a body of solution which tends to foam, which comprises in combination, a Wheatstone bridge, a control electrode

5 responsive to changes in concentration of said solution connected to one arm of said bridge, an auxiliary electrode connected in parallel in the circuit containing said control electrode, said auxiliary electrode being arranged above the normal level of said body of solution and, when contacted by foam, decreasing the resistance in said arm of said Wheatstone bridge, a control circuit in which said bridge is located, a relay operated by said control circuit, a main circuit, a switch in said main circuit operated by said relay, and means operated by said main circuit for dispensing detergent to said body of solution to maintain the concentration thereof within said narrow limits.

5. A control for controlling the concentration of a body of detergent solution which tends to foam, in combination, a dispenser for dispensing detergent solution to said body of solution, a control electrode disposed within said body of solution, an auxiliary electrode disposed above the normal level of said body of solution, a Wheatstone bridge, said control electrode and said auxiliary electrode being connected in parallel in a circuit connected with one arm of said bridge, a control circuit in which said Wheatstone bridge is disposed, a relay operated by said control circuit, a main circuit, a switch in said main circuit operated by said relay and a solenoid in said main circuit for effecting operation of said dispenser responsive to changes in concentration of said body of solution as indicated by said control electrode.
